UNITED STATES PATENT OFFICE.

ALBERT FALK, OF NEW YORK, N. Y., ASSIGNOR TO FALK TOBACCO COMPANY, OF NEW YORK, N. Y.

PACKING TOBACCO.

1,117,015.

Specification of Letters Patent.

Patented Nov. 10, 1914.

Application filed December 13, 1913. Serial No. 806,466.

To all whom it may concern:

Be it known that I, ALBERT FALK, a citizen of the United States, residing at New York, in the county of New York and State 5 of New York, have invented certain new and useful Improvements in Packing Tobacco, of which the following is a specification.

This invention relates to the subject of packing tobacco and like merchandise, and 10 the primary aim of the invention is to provide a package for such merchandise that is hermetically sealed against the admission of air and moisture so that deterioration of the contents of the package is prevented.

15 The invention contemplates a package including a main wrapper that is formed of material that is not affected by atmospheric influences, a seal for the wrapper that is also of material that is not affected by atmospheric influences and which prevents air or moisture gaining access to the contents of the main wrapper, or outer wrapper that encloses the main wrapper and seal, and which is adapted for advertisements, notices, and 20 25 25 a seal for the outer wrapper which, when tobacco or other taxed merchandise is contained in the package, may be a revenue stamp.

In carrying out the objects of the invention 30 as generally stated above, it will be apparent that the same is susceptible to changes in details and structural arrangements, one simple and practical embodiment being shown in the accompanying drawing, 35 wherein:—

Figure 1 is a perspective view of the improved package. Fig. 2 is a detail perspective view, the outer wrapper being removed and one end being shown unsealed. Fig. 3 40 is an end view showing the main wrapper sealed. Fig. 4 is a plan view of a sheet from which the inner wrapper is formed.

The improved package that forms the subject-matter of this invention is of special 45 utility in connection with smoking and other types of tobacco, but of course it is not limited to such use.

Referring to the accompanying drawings by numerals, it will be seen that the improved package comprises a main or inner wrapper 1 that is formed of comparatively heavy tin foil or other material which is not affected by atmospheric influences, said wrapper being preferably a sheet of material 50 55 which may be of the form shown in Fig.

4 of the accompanying drawing. The wrapper 1 is folded to provide a substantially flat rectangular package, the longitudinal meeting edges of the wrapper being overlapped, as indicated at 2, and pasted together. The meeting edges of the wrapper extend centrally and longitudinally of either the upper or lower broad surface of the package. The ends of the wrapper 1 are folded on the dotted lines indicated on Fig. 60 65 4 of the accompanying drawings to form the large rectangular flaps 3 through which the overlapped edges of the wrapper extend and which flaps lie against the ends of the contents of the package; the side flaps 4 70 which are triangular in shape and overlap the flaps 3; and the outer flaps 5 which overlap the flaps 3 and 4 and also the meeting edges of the wrapper 1 that extend through the flaps 3. By this arrangement of end flaps, 75 it will be seen that when the flaps are pasted together, the ends of the package are sealed.

The described manner of folding the ends of the wrapper 1 to provide the flaps that are overlapped and pasted together is a 80 convenient and efficient one, but the invention is not necessarily limited thereto.

When the wrapper 1 is folded about the tobacco or other merchandise, it will be seen that the meeting edges of the wrapper extend longitudinally of one broad surface of the package and across both ends, and in addition when the end flaps are employed, various overlapped edges occur, and to prevent air or moisture gaining access to the contents of the package, a sheet of tin foil 6, or other material that is unaffected by atmospheric influences, that is of a size to completely cover one broad surface of the wrapper and both ends of said wrapper is employed to seal such overlapped edges. This protecting strip or seal 6, is pasted over the surface of the wrapper 1 in which the longitudinal meeting edges of said wrapper are located and over the ends of the wrapper, and the ends of said strip may slightly overlap and be pasted to the opposite broad surface of the wrapper, as indicated at 7.

The protecting seal 6 is of thin material 105 compared to the wrapper 1, and when securely and smoothly pasted to said wrapper, is practically not noticeable. As stated, the protecting seal 6 covers only the side and ends of the wrapper 1, and such is preferred 110 115

instead of entirely inclosing the said wrapper, as such entire inclosing is not necessary for the reason that the overlapped edges are only at the ends and one surface 5 of the wrapper.

As described, it will be seen that the package comprises a main or inner wrapper that is securely folded about the contents of the package and that the main wrapper is preferably heavy tin foil or other air and moisture-proof material, and that said main wrapper is sealed at its meeting edges by a thin sheet of tin foil or other air and moisture-proof material. And the package may 10 be inclosed in a wrapper 8 of paper or other material adapted for advertisements, notices, etc. The ends of the wrapper 8 are folded to form overlapping flaps 9, which may be similar to the flaps of the wrapper 1. 15 The outer wrapper 8 has its longitudinal meeting edges 10 pasted together and loosely surrounding the package. The end flaps 9 are simply folded in overlapped relation, and are held in such position by means of 20 a seal 11 that is pasted over the meeting edges 10 and also over the end flaps. When tobacco or other taxed goods are contained 25 in the package, the seal 11 may be the revenue stamp. And it will be clear that the

seal 11 reinforces and protects the meeting 30 edges 10, and also prevents the flaps 9 accidentally opening.

What I claim as my invention is:—

1. A tobacco package comprising a wrapper of metal foil folded to form a container 35 having overlapped edge portions at one side and both ends, a sealing strip of metal foil of less body than the wrapper and applied to hermetically seal the overlapped edge portions of said wrapper, and an outer wrapper 40 inclosing the metal foil wrapper and the sealing strip.

2. A package of the character described comprising a main wrapper of air and moisture-proof material folded to form a container 45 having overlapped edge portions at one side and both ends, a protecting seal of air and moisture-proof material formed of a single sheet and overlapping and sealing said overlapping edge portions, and an outer 50 wrapper inclosing the main wrapper and seal.

In testimony whereof I have affixed my signature in presence of two witnesses.

ALBERT FALK.
